[57] CLAIM

The ornamental design for a dial card, as shown and described.

DESCRIPTION

FIG. 1 is a perspective view of a dial card showing my new design in a partially folded condition;

FIG. 2 is a front elevational view taken in the direction of line 2—2 of FIG. 1;

FIG. 3 is a top plan view taken in the direction of line 3—3 of FIG. 2;

FIG. 4 is a rear elevational view taken in the direction of line 4—4 of FIG. 1;

FIG. 5 is a top plan view thereof in the unfolded condition; and

FIG. 6 is a bottom plan view of FIG. 5.
